UNITED STATES PATENT OFFICE.

FRANCIS M. SWOPE, OF SEYMOUR, INDIANA, ASSIGNOR TO THE SEYMOUR MANUFACTURING COMPANY, OF SAME PLACE.

SCYTHE-SNATH FASTENING.

SPECIFICATION forming part of Letters Patent No. 283,932, dated August 28, 1883.

Application filed May 21, 1883. (No model.)

To all whom it may concern:

Be it known that I, FRANCIS M. SWOPE, of the city of Seymour, Jackson county, and State of Indiana, have made a new and useful Improvement in Scythe-Snath Fastenings, of which the following is a full, clear, and exact description, reference being had to the annexed drawings, making a part of this specification, in which—

10 Figure 1 is a face view of the improved fastening; Fig. 2, a side view; and Figs. 3 and 4, views in perspective of the fastening-plate and fastening-bolt respectively.

The same letters of reference denote the same 15 parts.

This invention is an improvement in that class of fastenings wherein provision is made for adjusting the blade to the desired inclination with the snath by means of a plate which 20 engages with the blade-shank, and is adapted to be swung upon and clamped to the snath.

The improvement consists in the special mode of constructing the swinging plate and clamp and combining them with the blade and each other.

25 A represents the lower end of an ordinary scythe-snath. The collar B is attached to the snath, and the scythe-blade C is secured by means of the eyebolt D, whose eye encircles 30 the blade-shank e, and whose stem passes through the collar and snath, and is fastened thereto, all in the usual manner. In place of notching the adjusting-plate E at its edge to engage with a pinion upon the clamping-bolt,

35 and pivoting the plate at its lower end to the snath at a point beneath the blade-shank, the plate is pivoted at its upper end, e, to the snath, and the socket e', to receive the toe e' of

the blade-shank, is at the lower end of the plate, and between its ends, at e², the plate is 40 slotted to receive the clamping-bolt F. At one edge of the slot, and in the face e³ of the plate, is a series of depressions, e⁴ e⁴. The bolt F is provided with a lateral projection, f, having one, and preferably two teeth, f' f', which 45 are adapted to engage in the depression e⁴ e⁴. These teeth, however, are not radial to the center of the bolt-stem f², but to the pivot. The scythe-blade is first set to the desired angle with the snath and then fastened by tightening the clamping-bolt. This draws the teeth f' f' into the depression e⁴ e⁴, and as long as 50 they remain therein the plate and blade are securely locked, for owing to the direction in which the teeth f' f' are extended—that is, 55 radially to the plate-pivot, and not to the bolt-stem—the bolt cannot be rotated in its bearing in the snath. However much leverage there is exerted by the blade upon the adjusting-plate, the bolt remains fast. To readjust the blade the bolt F must first be loosened and the teeth f' f' disengaged from the plate E. Then after the blade has been inclined as desired the bolt F is drawn again to bring the teeth into another set of the depressions e⁴ e⁴.

I claim—

The adjusting-plate E, pivoted, slotted, and having the depressions e⁴ e⁴, in combination with the clamping-bolt F, having one or more 70 teeth, f' f', extended, as described, substantially as and for the purpose set forth.

F. M. SWOPE.
